FOUNTAIN PEN CLIP

Clinton E. Marshall, Bronx, N. Y.

Application May 2, 1941, Serial No. 391,445

6 Claims. (Cl. 24—11)

This invention relates to fountain pen clips and the object of the invention is to provide a simple and economical means for securing and retaining the mounting end portion of the clip in connection with the cap of a fountain pen while at the same time producing a strong, well reenforced coupling of the clip and at the same time increasing the spring properties of the clip; a further object being to provide clip mounting of the class described comprising the formation of a prong on or projecting inwardly from the mounting portion of the clip and directed into the bore of the cap to be engaged by a plug arranged in said bore and forced against the mounting end of the clip so that the prong member pierces the plug thus keying and firmly retaining the mounting end of the clip in connection with the cap; and with these and other objects in view the invention consists in the device of the class and for the purpose specified, which is simple in construction and constructed as more fully hereinafter described.

The invention is fully disclosed in the following specification, of which the accompanying drawing forms a part, in which the separate parts of my improvement are designated by suitable reference characters in each of the views, and in which:

Fig. 1 is a longitudinal sectional view of the closed end portion of a fountain pen cap illustrating one of my improved clips supported therein.

Fig. 2 is a bottom plane view of a clip made according to my invention, showing the clip detached.

Fig. 3 is a section on the line 3—3 of Fig. 2.

Fig. 4 is a side elevation of the closed end of the cap showing the aperture formed therein for the reception of the mounting end portion of the clip; and

Fig. 5 is a view similar to Fig. 1 showing only a part of the construction and showing a modification.

In the construction and mounting of spring clips for the caps of fountain pens many forms of construction have been employed, for the most part these mountings have been more or less complicated and further a secure or firm mounting of the clip has not been provided. It is the purpose of my invention to provide a simple form of clip mounting wherein the mounting end of the spring arm, forming the clip, is provided with an inwardly extending prong fashioned from the material of this mounting end and which is adapted to pierce a plug member forced

into the bore of the cap to firmly and rigidly secure the clip to the cap and even to flex the mounting end of the cap so as to increase the tension or rigidity of this mounting.

In the drawing I have shown in Figs. 1 and 4, part of a fountain pen cap 10, one side wall of this cap adjacent the closed end 11 is provided with a substantially T-shaped aperture 12 preferably formed adjacent the inner surface 13 of the end 11, note Fig. 1, the leg 14 of the aperture 12 being substantially triangular in form and extends in the direction of the open end of the cap as clearly seen in Fig. 4. At 15 is shown one of my improved clips which comprises a spring arm 16 of channel cross-sectional form, the top wall of the channel at one end of the arm being curled inwardly as seen at 17, within the side flanges 18 at said end, to form in conjunction with the round contour of said flanges an enlarged rounded end for engaging the support, such as a pocket flap, in supporting a pen against displacement from a pocket. The other end of the spring arm terminates in an angularly extending mounting plate 19. This plate is of sufficient length to extend across the major portion of the bore 10a of the cap as noted in Fig. 1 of the drawing, the plate 19 being cut out as seen at 20 and then bent to form an inwardly directed pointed prong 21 which is positioned substantially centrally of the bore 10a.

It will thus be seen that in assembling the clip 15 with the cap 10 the plate 19 is passed through the aperture 12, the prong 21 passing through the triangular extension 14 of the aperture and the clip is moved inwardly until the side flanges 18 of the arm 16, adjacent the plate 19, engage the periphery of the cap 10. While held in this position a plug 22 is passed through the bore 10a and forced upon the plate 19 in which operation the prong 21 pierces the closed end wall 23 of the plug. This will securely lock and retain the clip against displacement from the cap. The plug 22 is more or less of a pressed fit in the bore 10a and in some instances a cement may be used to secure the plug in position.

In Fig. 5 of the drawing a slight modification of the construction is shown and in this figure 24 represents the closed end portion of a cap, the end wall being seen at 25 and the inner surface of this wall is made conical in form as seen at 26, and the plug 27 is beveled at its closed end as seen at 28 so as to urge or force the mounting plate 29 of the clip 30 into the recess 26 thus distorting the plate to provide a more

secure anchorage of the clip to the cap. The plug 27 will have centrally thereof a flat surface 31 to be engaged by the prong 32 similar in all respects to the prong 21 of the other figures. At 33 is shown the aperture in the wall of the cap 24 for receiving the mounting plate 29 and prong 32. As with the construction shown in Fig. 1, the prong 32 pierces the closed end of the substantially thimble-shaped plug 27 in firmly retaining the clip against displacement.

One of the distinctive advantageous features in applicant's structure resides in the fact that the entire clip is made from a strip of metal having limited width throughout its length. This reduces the cost of producing the clip while at the same time a strong and durable clip structure is provided. Further the fact that the prong element is disposed entirely within peripheral edges of the mounting plate not only maintains the strength of this plate, but again limits the dimensions thereof and at the same time localizes the prong at a point substantially at the axis of the bore of the cap. It will of course be understood that the spring arm of the clip may be made in many forms and stylings to suit the desires of the manufacturer and/or the ultimate consumer, and the present shape and contour is simply illustrative of one of the many types and kinds of clips that can be employed.

Having fully described my invention, what I claim as new and desire to secure by Letters Patent, is:

1. A clip for fountain pen caps, said clip comprising an elongated strip of material one end of which is fashioned to form an enlarged knob portion, the other end having an angularly extending mounting plate, said plate having a prong member extending in the direction of the first named end of said strip and arranged inwardly of the free end of said plate.

2. A clip for fountain pen caps, said clip comprising an elongated strip of material one end of which is fashioned to form an enlarged knob portion, the other end having an angularly extending mounting plate, said plate having a prong member extending in the direction of the first named end of said strip and arranged inwardly of the free end of said plate, and said prong being substantially triangular in form and formed from the material of the plate inwardly of the peripheral edges thereof.

3. A clip of the class described comprising an elongated strip of material channelled centrally thereof to form an elongated spring arm, one end of the strip being curled upon one side surface of the arm to form a gripper knob, the other end portion being extended substantially at right angles to the same side surface of the strip to form a mounting plate, and said mounting plate having within peripheral edges thereof a prong fashioned from the material of the plate and extending angularly to the plate in the direction of the first named end of said arm.

4. In combination with a fountain pen cap having an elongated bore extending to the closed end of the cap, the wall of the cap adjacent the closed end having a T-shaped aperture and a plug arranged in the bore adjacent the closed end thereof, of a clip comprising an elongated arm extending along the outer wall of the cap, the end of the clip adjacent the closed end of the cap having an angularly extending mounting plate extending into the bore of the cap adjacent said end wall, said plate having a prong projecting into the bore, and said prong being arranged inwardly of the free end of said mounting plate and substantially centrally of said bore, whereby in assembling the clip with the cap pressure feeding of the plug upon the surface of the mounting plate will cause the prong to pierce said plug in fixedly coupling the parts.

5. In combination with a fountain pen cap having an elongated bore extending to the closed end of the cap, the wall of the cap adjacent the closed end having a T-shaped aperture and a plug arranged in the bore adjacent the closed end thereof, of a clip comprising an elongated arm extending along the outer wall of the cap, the end of the clip adjacent the closed end of the cap having an angularly extending mounting plate extending into the bore of the cap adjacent said end wall, said plate having a prong projecting into the bore, said prong being arranged inwardly of the free end of said mounting plate and substantially centrally of said bore, whereby in assembling the clip with the cap pressure feeding of the plug upon the surface of the mounting plate will cause the prong to pierce said plug in fixedly coupling the parts, and the arm adjacent said mounting plate having side flanges engaging the wall of the cap limiting inward movement of the mounting plate.

6. In combination with a fountain pen cap having an elongated bore extending to the closed end of the cap, the wall of the cap adjacent the closed end having a T-shaped aperture and a plug arranged in the bore adjacent the closed end thereof, of a clip comprising an elongated arm extending along the outer wall of the cap, the end of the clip adjacent the closed end of the cap having an angularly extending mounting plate extending into the bore of the cap adjacent said end wall, said plate having a prong projecting into the bore, said prong being arranged inwardly of the free end of said mounting plate and substantially centrally of said bore, whereby in assembling the clip with the cap pressure feeding of the plug upon the surface of the mounting plate will cause the prong to pierce said plug in fixedly coupling the parts, and the end wall of said cap and adjacent surface of the plug being of irregular contour whereby the mounting plate is off-set within the bore of the cap upon insertion of said plug.

CLINTON E. MARSHALL.
